UNITED STATES PATENT OFFICE.

CHARLES A. NORLANDER, OF GREENVILLE, ILLINOIS, ASSIGNOR OF ONE-HALF TO
CHARLES E. DAVIDSON, OF GREENVILLE, ILLINOIS.

CARBURETOR.

1,423,579.

Specification of Letters Patent. Patented July 25, 1922.

Application filed May 9, 1921. Serial No. 467,867.

To all whom it may concern:

Be it known that I, CHARLES A. NORLANDER, a citizen of the United States, residing at Greenville, in the county of Bond 5 and State of Illinois, have invented a new and useful Carburetor, of which the following is a specification.

This invention relates to carburetors especially designed for use in connection with 10 natural or artificial gas as a fuel.

One of the objects of the invention is to provide a device of this character which will automatically regulate the supply of fuel to the engine, the construction of the carburetor being such that gas will be thoroughly 15 mixed with air in proper proportions.

Another object is to provide means whereby the amount of fuel admitted to the engine will depend upon the suction of the engine 20 so that the proper amount of fuel will be mixed with the air to produce the proper explosive mixture.

A still further object is to provide means whereby the supply of gas is automatically 25 cut off when the engine is not in operation, thus preventing leakage.

A still further object is to provide a carburetor of this type particularly designed for use in connection with a throttling governor whereby the supply of fuel to the engine will be automatically controlled.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention 35 shown can be made without departing from the spirit of the invention.

In the accompanying drawings the preferred form of the invention has been shown.

In said drawings—

45 Figure 1 is a side elevation of the carburetor.

Figure 2 is a vertical section therethrough.

Figure 3 is a section on line 3—3, Figure 1.

Figure 4 is a perspective view of the adjustable air tube.

Figure 5 is an elevation of the inner gas tube.

Referring to the figures by characters of

reference 1 designates the lower member of the body of the carburetor, the same being 55 provided with an enlarged upper end tube 2 counterbored as indicated at 3 to provide a seat. An interiorly threaded extension 4 is provided on the side of this lower section 1 and is designed to be engaged by the air 60 supply pipe 5. The lower end of the section 1 is closed by a plug 6 which can be connected to the section 1 in any manner desired and has a central opening 7 therethrough constituting a continuation of the space within an outer gas tube 8 which is integral with and extends upwardly from the plug 6. A tubular extension 9 projects downwardly from the plug and has its lower end portion provided with both interior and 70 exterior screw threads as shown at 10. Openings 11 are formed in this extension 9 and communicate with the interior of a supplemental casing 12 which is fitted snugly on the extension 9 and provides an annular 75 gas chamber 13 with which the openings 11 communicate. An inlet tube 14 is formed with and extends radially from the wall of the casing 12 and is adapted to be connected to a gas supply tube or pipe 15.

An inner gas tube 16 is insertable into the opening 7 in the plug 6 and has its lower end extending downwardly within the space surrounded by the extension 9 and exteriorly screw threaded, as at 17, so as to engage the 85 interior screw threads on the lower end 10 of the extension 9. The lower end of this inner tube 16 is solid and is adapted to be engaged by a packing nut 18. Another nut 19 engages the exterior threads on the lower 90 end portion 10 of the extension 9 and constitutes a lock nut for bearing against the bottom of the casing 12. Packing, indicated at 20, is interposed between the two nuts 18 and 19 so as to seal the joint between the extension 9 and the threaded portion of the inner gas tube 16. An angular head 21 may be formed on the lower end of the inner tube 16 whereby said tube can be readily screwed into or out of position by the use 100 of an ordinary wrench. Radial openings 22 are provided in the inner tube 16 and communicate with the annular space formed between the extension 9 and the outer tube 8.

The upper end portion of the tube 16 105 terminates below the upper end of the tube

8 and has its exterior diameter reduced, this reduced portion being slotted longitudinally as shown at 23.

Firmly seated in the counterbore 3 is a bearing ring 24 which projects beyond the upper end of the section 1 and is provided with an annular groove 25. In this ring is adjustably mounted a flared tube or ring 26 from which depends an arm 27 engaged by 10 a clamping screw 28. This screw extends through a longitudinal slot 29 in the section 1 of the casing and it will be obvious that by loosening the screw the flared tube can be adjusted upwardly or downwardly 15 and then fastened. It will be noted that the passage within the flared tube decreases in diameter toward the lower end thereof and that the lower end of this passage is normally slightly above the upper end of the 20 gas tube 8.

Mounted for rotation on the bearing ring 24 is the upper section 30 of the carburetor casing, the lower open end of this section being counterbored so as to fit snugly on 25 the projecting portion of the ring 24 and being held to said ring by a key or pin 31 which rests within the groove 25 but is capable of sliding within the groove during the rotation of the section 30 upon the ring 30 24. This upper section 30 is closed at its upper end except for a threaded bore 32 in which is mounted a threaded tube 33 having a head 34 at its upper end. This tube constitutes a guide for a stem 35 to 35 the lower end of which is connected a disk or diaphragm 36 mounted within the flared tube and spaced therefrom. A central boss 37 is provided upon the lower face of the disk or diaphragm 36 and carries a washer 40 or valve 38 of leather or the like adapted to contact with the upper end of the tube 8. A conical deflector extends downwardly from the lower face of the washer, as shown at 39 and depending from the center of this 45 deflector is a fuel pin 40 which is slidable within the slotted portion of the tube 16 and has an enlarged lower end portion 41 which fits snugly within the tube. A spring 42 is mounted on the stem 35 and bears at its 50 lower end against the diaphragm or disk 36 and at its upper end against the tube 33. Thus the washer 38 is held normally pressed against the tube 8, the tension of the spring 42 being regulated readily by adjusting the 55 tube 33. A lock nut 43 is mounted on the tube 33 and normally bears against the upper end of the section 30 so as to secure the tube against movement.

A fuel outlet pipe 44 extends radially 60 from the section 30 and contains a butterfly valve 45 mounted on a stem 46. This stem is mounted for rotation and has a radial arm 47 at one end especially adapted to be connected to a suitable governor whereby, as 65 the speed of the engine increases the arm

47 will be shifted so as to partly or entirely close the outlet tube 44 at the valve 45. The movement of the arm 47 can be limited by a stop screw 48 carried by an arm 49 extending from the section 30.

Assuming that the butterfly valve 45 is open and that the engine is in operation, it will be apparent that each suction stroke of the engine will cause air to be drawn through the pipe 5 and thence through the 75 flared tube 26, the force of the air being sufficient to lift the disk or diaphragm 36 against the spring 42 so as thereby to raise the washer 38 off of the end of the tube 8. Consequently a suction will be set up 80 through the tube 8 from the interior of the tube 16 so that gas will be sucked from the pipe 15 through the openings 11 into the openings 22 and tube 16 and thence through the slots 23 in the outer tube 8. When the 85 diaphragm 36 is raised the pin 40 is also raised so that the amount of gas escaping through the slots 23 is thus controlled, this amount varying in proportion to the amount of movement of the diaphragm 36. When 90 the engine is not in operation the spring 42 will hold the washer 38 pressed against the tube 8 so as to prevent leakage of gas.

By mounting the section 30 so as to swivel on the section 1, the carburetor can be adjusted for ready connection to engines of different types. It will be noted also that the casing 12 can be adjusted angularly by loosening the nut 19.

What is claimed is:—

1. In a carburetor the combination with a casing having an air inlet and a fuel outlet, of a diaphragm in the path of the air passing from the inlet to the outlet, a gas conducting tube within the casing, means movable with the diaphragm and normally engaging the end of the tube to close the gas outlet of the tube, an inner gas conducting tube having an outlet, and means within the inner gas conducting tube and movable with the diaphragm for regulating the flow of 100 gas from the inner tube to the outer tube.

2. In a carburetor the combination with a casing having an air inlet and a fuel outlet and a flared tube adjustably mounted between said inlet and outlet, of a gas tube, a yieldingly restrained diaphragm movably mounted within the flared tube, and a valve movable with the diaphragm and normally closing the outlet end of the gas tube, an inner tube within the gas tube having a gas inlet and a longitudinal outlet, and means within the inner tube and movable with the valve and diaphragm for controlling the flow of gas from the inner to the outer tube 115 when the valve is unseated.

3. In a carburetor the combination with a casing having an air inlet and a fuel outlet and a flared tube adjustably mounted between said inlet and outlet, of a gas tube, a 120

- yieldingly restrained diaphragm movably mounted within the flared tube, and a valve movable with the diaphragm and normally closing the outlet end of the gas tube, an inner tube within the gas tube and having a gas inlet and a longitudinal gas outlet, and means movable with the diaphragm and valve for regulating the flow of gas from the inner to the outer tube during the movement of the valve off of its seat and in proportion to the amount of such movement.
4. In a carburetor the combination with a casing having an air inlet and a fuel outlet, of a gas tube opening into the casing, a diaphragm movably mounted in the casing between the inlet and outlet, adjustable means for yieldingly holding the diaphragm against movement, a valve movable with the diaphragm and normally seated on the gas tube to close the outlet end of the tube, and means movable with the valve and within the gas tube for controlling the flow of gas from the tube when the valve is unseated.
5. In a carburetor the combination with a casing having an air inlet and a fuel outlet, of a gas tube opening into the casing, a diaphragm movably mounted in the casing between the inlet and outlet, adjustable means for yieldingly holding the diaphragm against movement, a valve movable with the diaphragm and normally seated on the gas tube to close the outlet end of the tube, and
- means movable with the valve and within the gas tube for controlling the flow of gas from the tube when the valve is unseated, 35 the amount of gas released increasing in proportion to the extent of movement of the valve away from its seat, and means movable with the valve for deflecting the escaping gas to effect a thorough mixing thereof 40 with the air in the casing.
6. In a carburetor the combination with a casing having an air inlet and a fuel outlet, of a tube projecting into the casing for delivering gas into the current of air passing from the inlet to the outlet, an inner tube within said tube and having a gas inlet and a longitudinal gas outlet, a diaphragm movably mounted in the casing, a valve movable therewith, yielding means for resisting the 50 movement of the diaphragm and for holding the valve normally seated upon the outlet of the outer tube, a pin movable with the valve and within the tube for controlling the flow of gas through the longitudinal outlet in the 55 inner tube.

In testimony that I claim the foregoing as my own, I have hereto affixed my signature in the presence of two witnesses.

CHARLES A. NORLANDER.
